UNITED STATES PATENT OFFICE

GEORGE S. GATCHELL, OF ROSELLE PARK, NEW JERSEY, ASSIGNOR TO THE SINGER
MANUFACTURING COMPANY, OF ELIZABETH, NEW JERSEY, A CORPORATION OF
NEW JERSEY

LOOP-FORMING DEVICE FOR SEWING MACHINES

Application filed March 30, 1927. Serial No. 179,426.

This invention relates to sewing machines and more particularly to devices for insuring that the needle-thread loops will be formed at the proper side of the needle or needles for seizure by the loop-taker.

An object of the invention is to provide a movable loop-forming device of simplified construction which may be applied to or removed from the machine as a unitary assembly independently of the machine mechanism and which, when applied, will be operated by a moving part of the machine, without the necessity of providing the machine with a special driving connection for such device. A further object of the invention is to provide a movable loop-forming device which is adapted for unitarily detachable mounting independently of the machine mechanism in a sewing machine having a rocking and sliding looper-shaft and, more specifically, within the end-cap of a cylinder-bed sewing machine. A further object of the invention is to provide the device with means for accurately adjusting its working positions.

To the attainment of the ends in view, the device, in its preferred embodiment, is constructed with a horizontally disposed supporting post, adapted to be attached to the end-wall of the cylinder-bed casting of the machine below the looper-shaft. The supporting post pivotally carries at its outer end an upstanding holder for a flat loop-engaging blade which is arranged to be moved to a working position closely adjacent the outer side of the needle or needles.

As the needles rise the blade prevents expansion of the new needle-loops at the outer side of the needles and insures that the loops will expand fully at the inner side of the needles in the path of the advancing looper.

An adjusting screw carried by the pivoted holder bears upon a stop-lug on the post to permit accurate adjustment of the working position of the blade adjacent the needles.

A second adjusting screw carried by the holder is directed toward the end of the looper-shaft and is engaged and shifted by the latter, during the needle-avoiding movement of the looper, to move the loop-former away from the outer side of the needles to

clear the way for the receding movement of the looper.

A spring secured to the post bears upon the carrier to urge the loop-former at all times toward the needles, so that as the looper is given its sidewise movement preparatory to its advance, the loop-former is moved up to working position adjacent the needles. The entire device, including the post, pivoted holder, blade, and adjusting screws, may be applied to or removed from the machine as a unitary assembly and requires no actuating cam or eccentric on the looper-shaft or additional working part within the cylinder-bed for its operation.

In the accompanying drawings illustrating the invention in its preferred form, Fig. 1 is a side elevation, partly in section of the sewing end of a cylinder-bed chain-stitch sewing machine, with the looper advancing. Fig. 2 is a front end view. Fig. 3 is a side elevation of the stitch forming instrumentalities with the looper receding. Fig. 4 is a similar view with the needles in their lowest position.

1 represents the cylinder-bed of a sewing machine having a head 2 carrying the needle-bar 3 and a presser-bar 4 which carry, respectively, the reciprocating needles 5 and presser-foot 6.

Cooperating with the presser-foot 6 to feed the work is the four-motion feed-dog 7 carried by the feed-bar 8. The throat-plate is shown at 9 and the end-cap at 10.

Journalized within and lengthwise of the cylinder-bed 1 is the usual rocking and sliding looper-shaft 11 carrying the threaded looper 12 which advances along the inner side of the needles to seize the needle-loops, as shown in Figs. 1 and 2, and recedes along the outer side of the needles, as shown in Fig. 3, to shed the needle-loops.

Detachably mounted on the free end-wall of the bed 1 by screws 13 is the horizontally disposed supporting post 14 which pivotally carries at 15 the holder 16 for the flat loop-engaging blade 17 which is wide enough to engage the loops of both needles 5. The post 14 is formed with a stop-lug 18 for the adjusting screw 19 carried by the holder 16.

The spring 20 secured to the post 14 by the screw 21 bears inwardly at its upwardly curved free end upon the holder 16 and biases the holder and loop-engaging blade toward the needles; the stop-screw 19 being adjusted to correctly position the blade 17 close to the needles, so that as the needles rise the needle-loops will be caused to expand substantially wholly at the inner side of the needles. A second adjusting screw 22 carried by the holder is directed toward the free end of the looper-shaft 11 and is engaged by the latter during its outward sliding movement to shift the loop-forming blade away from the needles in time with the needle-avoiding movement of the looper, and thus clear the way for the recession of the looper. Adjustment of the screw 22 determines the distance away from the needles to which the loop-former will be shifted by the looper-shaft. This distance should be just sufficient to permit free passage of the looper blade.

It will be observed that in the position of the parts shown in Fig. 4 the looper-shaft is out of engagement with the end of the screw 22. Thus the looper-shaft partakes of a certain amount of endwise movement before it strikes the screw 22 and moves the loop-forming device. This intermittent contact between the looper-shaft and the screw 22 permits the loop-forming device to dwell or remain stationary in loop-forming position while the needles are rising to throw out their loops. The period of dwell of the loop-forming device may be adjusted by adjusting the screw 22.

By removing the screws 13 the complete loop-forming device may be removed as a unitary assembly and, when replaced, will be operatively related to the looper-shaft to be properly actuated by the latter without special or additional mechanism within the cylinder-bed where space is at a premium.

Having thus set forth the nature of the invention, what I claim herein is:—

1. The combination with a sewing machine having a reciprocating needle and a rocking and sliding looper-shaft, of a loop-forming device detachably mounted as a unitary assembly at the end of said looper-shaft, independently of the sewing machine mechanism, and including a loop-engaging member movable laterally toward and away from the needle in timed relation with the advance and recession of the looper.

2. The combination with a sewing machine having a reciprocating needle and a rocking and sliding looper-shaft, of a loop-forming device detachably mounted as a unitary assembly at the end of said looper-shaft and including a support, a loop-engaging member pivotally carried by said support and adapted to be shifted by endwise movement of the looper-shaft.

3. The combination with a sewing machine

having a reciprocating needle and a rocking and sliding looper-shaft, of a loop-forming device including a pivotally mounted loop-engaging member, an adjusting screw carried by said member and adapted to be engaged by the looper-shaft, during the latter's sliding movement, and a spring for biasing said member toward the looper-shaft.

4. The combination with a sewing machine having a reciprocating needle and a rocking and sliding looper-shaft, of a loop-forming device including a pivotally mounted loop-engaging member, an adjustable stop-screw carried by said member, a stop engaged by said screw to limit the movement of said loop-engaging member toward the needle, a spring for biasing said member to loop-engaging position, and means for shifting said member away from said needle during the sliding movement of the looper-shaft.

5. The combination with a cylinder-bed sewing machine having a reciprocating needle and a rocking and sliding looper-shaft disposed lengthwise of and within the cylinder-bed, of a supporting post detachably mounted on the free end-wall of the cylinder-bed below the looper-shaft, a loop-engaging member pivotally carried by said post, coacting stop and adjusting screw means carried by said post and member for determining the loop-engaging position of the latter, a spring for biasing said member to loop-engaging position, and means for periodically shifting said member away from loop-engaging position.

6. The combination with a sewing machine including a reciprocating needle and four-motion looper-mechanism, of a loop-forming device movably mounted adjacent the needle-path independently of the looper-mechanism and intermittently engaged and actuated by the looper-mechanism.

In testimony whereof, I have signed my name to this specification.
